[57] CLAIM

The ornamental design for a capsule chamber for mixing additives into a paint container or similar article, as shown and described.

DESCRIPTION

FIG. 1 is a top perspective view of a capsule chamber for mixing additives into a paint container or similar article showing my new design;

FIG. 2 is a bottom perspective view thereof;

FIG. 3 is a top plan view thereof;

FIG. 4 is a bottom plan view thereof;

FIG. 5 is a front elevational view thereof, the rear, left and right side views all being identical; and,

FIG. 6 is a cross-sectional view thereof, taken on line 6—6 of FIG. 5.

FIG. 1

FIG. 2

FIG. 3

FIG. 4

FIG. 5

6

6

FIG. 6
